[57] CLAIM

The ornamental design for a shoe and boot cleaner, as shown and described.

DESCRIPTION

FIG. 1 is a top and left front perspective view of my shoe and boot cleaner design;

FIG. 2 is a right end elevation;

FIG. 3 is a top plan view;

FIG. 4 is a bottom plan view; and,

FIG. 5 is a rear elevation.

The cross hatching and the shading depicting bristles in the figures is fragmentarily shown for convenience of illustration, it being understood that the shading is uniformly continuous over the surface on which it appears.
